UNITED STATES PATENT OFFICE.

JOHN TAYLOR AND LUDWIG WILLIAM WEIL, OF MANCHESTER, ENGLAND.

CENTRIFUGAL PUMP.

1,125,763.

Specification of Letters Patent.

Patented Jan. 19, 1915.

Application filed November 23, 1912. Serial No. 733,071.

To all whom it may concern:

Be it known that we, JOHN TAYLOR and LUDWIG WILLIAM WEIL, respectively, subjects of the King of Great Britain and Ireland and the Emperor of Austria-Hungary, and residents of Manchester, in the county of Lancaster, England, managing director and engineer, respectively, have invented certain new and useful Improvements in 10 Centrifugal Pumps, of which the following is a specification.

Our invention relates to improvements in rotary pumps of the centrifugal, turbine or like types in which a certain static or dynamic head or pressure is obtained by imparting to the fluid to be pumped a certain amount of kinetic energy by means of a bladed disk, runner, impeller or like device rotating at a speed which is determined by 15 the amount of total pressure required. The kinetic energy so produced is then converted into a static pressure in the fixed casing of the pump. This conversion has, previous to the date of our invention been accomplished either in a number of passages symmetrically arranged around the outside periphery of the said impeller as in a pump of the turbine type, or in a single receiving 20 or collecting chamber which surrounds the impeller directing the fluid to the discharging orifice of the pump, which is usually a continuation of the chamber referred to. The first arrangement has the advantage of a high hydraulic efficiency even when 25 working against very high heads, but this high efficiency is only obtained when the pump is running under such conditions as regards speed, output, and head for which the guide 30 passages and impellers have been specially 35 designed. On the other hand this efficiency quickly falls under varying conditions of working. The second or ordinary centrifugal pump arrangement is not subject to the same disadvantage as it has only one 40 collecting chamber to receive and guide the fluid upon leaving the impeller. For this reason it is suitable for wider variations of output and speed. Owing to the fact, however, that it has only a single collecting or 45 whirlpool chamber, the streams of fluid which are thrown from the impeller, baffle each other in this chamber to a certain extent, with the result that a very low hydraulic efficiency is obtained which renders 50 this type of pump particularly unsuitable

for delivering against medium or high heads.

Our invention is designed with the object of overcoming the disadvantages of both the foregoing types while retaining 55 their advantages and thereby enabling a high hydraulic efficiency to be obtained, over a large range of duties comprising wide variations of speed, output and head; the improved pump being capable of not only 60 delivering against low heads, but also against comparatively high heads with 65 high efficiencies.

To this end our invention consists essentially in means for converting the kinetic 70 energy imparted to the fluid by the impeller into pressure, such means comprising a chamber in which the impeller is located; an annular nozzle-shaped receiving chamber of gradually increasing sectional area 75 so communicating with said chamber; a single guide vane and a spiral or volute collecting chamber, the nozzle chamber and guide vane, changing the direction of motion of the fluid away from the impeller into the 80 spirally-arranged or volute chamber or gradually increasing cross section, communicating with the discharge outlet of the pump.

Our invention will be fully described with 85 reference to the accompanying drawings which show an example of how we carry out the invention and in which—

Figure 1 is a sectional front elevation of the improved pump, Fig. 2 a side elevation of the right hand half of the pump with the 90 impeller removed and Fig. 3 a sectional side elevation of the impeller.

In the drawings *a* and *b*, are, respectively, the inlet and discharge halves of the pump casing, *c* being the fluid inlet and *d* the discharge outlet, *e* the shaft and *f* the impeller fixed thereon. The impeller is of the ordinary construction, provided with vanes or blades *g* as will be well understood flanked by inclosing disks or flanges *h*, the outer one 95 of which is coned at the center to direct the fluid to the impeller vanes. The inner face *i* of the inner flange *h* of the impeller is substantially in the same plane as the flanged edge *j* (forming part of an annular nozzle-shaped chamber) of a partition *k* and in accordance with our invention the fluid, after leaving the periphery of the impeller, is diverted into the aforesaid annular nozzle-shaped chamber or passage *m* which is, pref- 100 105 110

erably, of parabolic design, from a plane parallel to the axis of rotation of the shaft e into a plane vertical to the axis of rotation. This passage is also constructed so that a 5 partial twist is imparted to the passing fluid for the purpose of changing its direction from that of a plane parallel to the axis of rotation of the impeller to a plane substantially vertical to such axis. A single guide 10 vane o is located in the aforesaid nozzle chamber m and its function is to determine the correct theoretical direction of the fluid through the nozzle-shaped receiving chamber m , and also to prevent the impeller from 15 causing the water in the chamber to rotate in planes concentric to the axis of rotation as is the case in centrifugal pumps of the usual design. In other words the guide vane o is formed so as to correspond with 20 the correct theoretical path of the fluid through the annular nozzle shaped chamber m , that is to say, it starts with a horizontal edge n or tip adjacent to the periphery of the impeller and follows the twist which is 25 imparted to the fluid in its passage from the impeller through the annular nozzle shaped passage m , gradually vanishing into the wall of the spiral or volute chamber.

In the pump shown, the spiral guide vane 30 or web o extends around the upper one half of the passage through the pump, its ends being arranged on opposite sides of the axis of the shaft e and a little below it.

This combination of parts, the nozzle 35 chamber and guide vane performs the conversion of the kinetic to static energy, firstly by a powerful reaction effect in the nozzle-shaped receiving chamber m and secondly, by gradual expansion owing to increased sectional area of that chamber and the spiral 40 chamber p forming a continuation of it to the discharge outlet d , thus giving the highest possible hydraulic efficiency. This arrangement with only one guide vane allows 45 of a great variation of output with a very small variation in efficiency. This is due to the fact that any variation from the normal conditions for which the pump is designed can only entail a slight loss at the impeller 50 area near the tip of the single guide vane, the fluid issuing from the remainder of the area finding its own path in accordance with the varied hydraulic conditions without loss

due to shock or eddy. The single vane, as already stated, leads into the spiral casing 55 or chamber p which is so designed as to guide the fluid from the whole periphery to the discharge orifice d , so as to insure a steady undisturbed movement of the whole body of the fluid at an equal velocity after 60 it leaves the nozzle-shaped receiving chamber. Thus the fluid is delivered from the latter into the surrounding spiral chamber, again without any shock or eddy. The powerful reaction effect in the aforesaid 65 nozzle-shaped receiving chamber produces an efficient self-regulating effect in the pump. Then should the external head or resistance suddenly fall from any cause, such as breakage of pipes, valves, etc., an increased 70 quantity delivered by the pump would cause a great reaction effect in the nozzle-shaped receiving chamber, and would thus confine the quantity and power required to the limit for which the pump is 75 designed. This self regulation is accomplished without any marked decrease in efficiency on the part of the pump.

The pumps are made in various sizes for 80 a given range of service.

What we claim as our invention and desire to secure by Letters Patent is:—

The combination, with a rotary impeller, of a casing inclosing the impeller and provided with an inlet at its axis and an outlet 85 at its periphery, said casing having an annular port for receiving the liquid from the periphery of the impeller and having an annular passage of gradually increasing area arranged behind the impeller and extending circumferentially of its axis from the annular port to the said outlet, said casing having also a spiral guide vane curved eccentrically of the impeller axis and arranged diagonally of the said passage and 90 operating to modify the direction of the liquid passing through it and cause the liquid to rotate in the outlet as set forth.

In testimony whereof we have hereunto set our hands in the presence of two witnesses. 100

JOHN TAYLOR.
LUDWIG WILLIAM WEIL.
